nership

Application May 22, 1946, Serial No. 129,979

Term of patent 3½ years

(Cl. D63—1)

To all whom it may concern:

Be it known that I, Kurt Meister, a citizen of the United States of America and a resident of New York, in the county of New York and State of New York, have invented a new, original, and ornamental Design for a Dental Press, of which the following is a specification, reference being had to the accompanying drawing, forming a part thereof.

In this drawing:

The figure is a perspective view of a dental press, showing my new design. The other side, not shown, is substantially like the side shown.

I claim:

The ornamental design for a dental press, as shown and described.

KURT MEISTER.
